UNITED STATES PATENT OFFICE.

ALANSON M. POND, OF DUBUQUE, IOWA.

GREASE-CUP.

1,300,009.

Specification of Letters Patent.

Patented Apr. 8, 1919.

Application filed June 21, 1917. Serial No. 175,997.

To all whom it may concern:

Be it known that I, ALANSON M. POND, a citizen of the United States, and a resident of the city of Dubuque, in the county of Dubuque and State of Iowa, have invented certain new and useful Improvements in Grease-Cups; and I do hereby declare that the following is a full, clear, and exact description of the same, reference being had to the accompanying drawings, and to the numerals of reference marked thereon, which form a part of this specification.

This invention relates to an improved type of quick adjustable grease cup adapted for any purpose wherein the cap of the grease cup may be operated inwardly by either a direct movement or rotational adjustment on the base. However, the cap may only be removed from the base by an unthreading operation, thus obviating possibility of loss of the cap.

It is an object therefore of this invention to construct a grease cup provided with a cap which may be positively thrust inwardly on the base of the device without rotational movement, or rotated to thread the same inwardly upon the base.

It is also an object of this invention to construct a grease cup comprising a threaded base, and a cap provided with resilient toothed members for engagement with the threads of the base whereby the cap may be threaded on or off the base, as well as thrust inwardly without rotation upon said base due to springing of said toothed members over the threads, thus permitting rapid adjustment of the cap upon the base.

It is furthermore an object of this invention to construct a quickly adjustable grease cup device wherein co-acting resilient members are provided between the base and cap of the device permitting quick adjustment of the cap upon the base, and yet necessitating a rotational threading movement thereof to detach the cap from the base.

Other and further important objects of this invention will be evident from the disclosure in the drawings and specification.

The invention (in a preferred form) is illustrated in the drawings and hereinafter more fully described.

On the drawings:

Figure 1 is a central vertical section taken through a device embodying the principles of my invention with parts shown in elevation.

Fig. 2 is a section on line 2—2 of Fig. 1.

Fig. 3 is an interior plan view of the cap shown in Fig. 2.

Fig. 4 is an enlarged sectional detail showing the relation of a resilient member and threads of the device.

Fig. 5 is a view similar to Fig. 1, of a modified type of device.

Fig. 6 is an exterior view of the cap member of the modification.

Fig. 7 is an interior plan view of the cap member shown in Fig. 6.

Fig. 8 is a view similar to Fig. 1, of another modified form of device.

Fig. 9 is an exterior side view of the base member of the modification.

Fig. 10 is a top plan view thereof.

As shown on the drawings:

The device comprises a conventional tubular base member 1, the lower end of which is threaded to permit attachment thereto into a mechanism to be lubricated, and provided with threads 3, on the upper portion thereof. The cap for the grease cup consists of a metal shell or casing 4, into which the lubricant is packed, and secured on the interior of said cap is a U-shaped resilient strap 5, secured in place by a central rivet 6, with the ends of said strap bent inwardly to afford engaging teeth 7, for co-action with the threads 3, of the base member 1. The cap 4, is stamped or otherwise formed outwardly, as denoted by the reference numeral 8, at the points in the side walls registering with the lower ends of the strap 5, to permit the lower ends thereof on which the teeth 7, are provided to spring outwardly over the threads 3, of the base, when the cap is thrust inwardly.

In the form of device illustrated in Figs. 5, 6 and 7, the base member 1, as shown on the previous construction is used, having the exterior upper threads 3, and the lower exterior threads 2. The cap member, however, is of slightly different construction, and is denoted as a whole by the reference numeral 9. Near the lower end of the cap member on opposite sides thereof, the walls are slotted to afford integral resilient members 10, which, at their lower ends, are provided with engaging teeth 11, for co-action with the threads 3, on the base member, and said members spring outwardly when the cap 9, is thrust inwardly without rotation.

In the form of device illustrated in Figs. 8, 9 and 10, I have shown a cap member 12,

which is interiorly threaded as denoted by the reference numeral 13, and the base member denoted as a whole by the reference numeral 14, is constructed as hereinafter described to receive the cap member engaged therewith. The upper portion of the base member 14, on each side is provided with vertical slots diametrically disposed on the exterior surface, and mounted in each thereof are resilient members 15, the upper ends of which extend above the upper end of the base member and are provided with outwardly formed toothed members 16, for co-action with interior threads 13, of the cap 12.

15 The operation is as follows:

In the form of device illustrated in Figs. 1 to 4, inclusive, if it is desired to attach or adjust the cap 4, inwardly upon the base 1, of the device, the cap is merely thrust inwardly under pressure, thereby causing the inclined toothed members 7, to ride over the threads 3, of the base 1, until the desired point of adjustment of the cap has been reached, that is, after a certain quantity of 20 the lubricant contained within the cap 4, has been forced through the base 1, to the mechanism to be lubricated. In the event that the lubricant should have become hardened so as to resist easy adjustment inwardly of the cap 4, under pressure, the cap 4, may be rotated, thereby screwing the cap 4, upon the base 1, with the toothed members 7, engaging and co-acting with the threads 3, for the purpose, thus obtaining a 25 considerable leverage effect to force the grease from the device into the mechanism. However, in order to detach the cap 4, from the device, it is necessary to rotationally adjust the same, thereby unthreading the cap 30 from the base. The necessity for this operation precludes accidental detachment and loss of the cap from the device.

In the form of device illustrated in Figs. 45 5 to 7, inclusive, the operation is identical, the only difference being that the resilient members 10, provided with the engaging teeth 11, for co-action with the threads 3, of the base, are formed integral with the metal cap 9.

50 In the form of device illustrated in Figs. 8 to 10, inclusive, I have shown the toothed resilient members associated with the base member 14, of the device, and with the interior of the cap 12, threaded for co-action therewith. In this construction, as in the preceding constructions described, the cap may be adjusted inwardly upon the base 14, either by thrusting the same inwardly and causing the toothed members to click over the threads 13, or by rotational adjustment 55 of the cap 12, to thread the same inwardly upon the base members by co-action with said resilient toothed members. Likewise, in order to detach the cap from the device, 60 it is necessary to rotate the same to un-

thread the cap from engagement with the toothed members 16. Obviously, the device is susceptible of many other modifications not shown, and I therefore do not purpose limiting the patent granted except as necessitated by the prior art.

I claim as my invention:

1. A grease cup comprising a screw threaded base member, a cap member adapted to telescope thereon, and oppositely disposed resilient members secured to the cap having their ends shaped to provide teeth adapted to spring outwardly to pass over the screw threads on the base member without rotation of the cap when the cap 80 is telescoped on the base member and adapted to engage the screw threads to prevent removal of the cap except by rotation.

2. In a device of the class described, a screw threaded base member, a cap therefor, and resilient means on said cap adapted to engage said screw threaded base member permitting adjustment of the cap under stress without rotation thereof and preventing separation of the cap and base member 90 except by rotation of the cap.

3. A device of the class described comprising two members, one provided with screw threads, and resilient means associated with the other member adapted to 95 slip over the screw threads for direct association of the members and adapted to engage the screw threads necessitating rotation of one of the members in separating the members.

4. In a device of the class described, a base member, a cap member adapted to be telescoped thereover, and co-acting means on said members adapted to permit the cap being inserted on the base member without 105 rotation thereof and permitting removal thereof only by rotation.

5. In a device of the class described, a base member externally screw threaded at its upper end, a cap member of sufficient 110 diameter to loosely telescope over said screw threaded end, and a plurality of resilient tooth members on said cap member adapted to engage said screw threads permitting the cap to be inserted thereon without rotation thereof and preventing removal of the cap from the base except by rotating the cap.

6. A grease cup comprising a base member and a cap member, one of which is provided with screw threads, and the other of 120 said members having resilient members secured thereto, each of which is adapted to pass over the screw threads in forcing the members together and which is adapted to prevent separation of the members except 125 by rotating one member relatively of the other.

7. A grease cup comprising a base member, a cap member and co-acting means on said members adapting the cap member to 130

be disposed on the base member, without rotation thereof and to lock the cap member thereon in any position and permitting the cap to be removed from the base member only by rotation of the cap member relatively of the base.

In witness whereof I have hereunto sub-

scribed my name in the presence of two subscribing witnesses.
